Attorneys,

UNITED STATES PATENT OFFICE.

LUTHER S. KLING, OF DUNCANNON, PENNSYLVANIA.

JEWELING-TOOL.

SPECIFICATION forming part of Letters Patent No. 512,653, dated January 9, 1894.

Application filed June 11, 1892. Serial No. 436,379. (No model.)

To all whom it may concern:

Be it known that I, LUTHER S. KLING, a citizen of the United States, residing at Duncannon, in the county of Perry and State of Pennsylvania, have invented certain new and useful Improvements in Jeweling-Tools; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to an improved jewel-
ing tool for producing the countersink or set-
ting for jewels in watches with precision and
expedition, and to these ends the invention
consists in the provision of a carrier or car-
riage adapted to be held in the tail-stock of a
lathe, when it is operated, and carrying a
movable cutter holder or slide combined with
novel means to provide for sundry adjust-
ments of said cutter holder or slide with its
cutter, substantially as hereinafter fully dis-
closed and pointed out in the claims.

In the accompanying drawings:—Figure 1
is a perspective view of my improved jewel-
ing tool. Figs. 2 and 3 are opposite end views
thereof. Fig. 4 is a transverse section, and
Fig. 5 a longitudinal section of the same.
Fig. 6 is an enlarged detached view, showing
more fully the tool or cutter holder, or slide
and adjunctive parts; and Fig. 7 is a similar
view of the index actuated by said cutter
slide or holder, and a follower carried by said
index.

In the embodiment of my invention, I em-
ploy a carrier or carriage A, preferably of the
construction as shown most clearly in Fig. 1,
consisting of an oblong portion *a* and a rect-
angular portion or plate *a'* screwed or other-
wise suitably secured at or along one of its
longer edges upon the part A. The oblong por-
tion or part *a* of the carrier or carriage A, while
preferably square in its external cross sec-
tion, is tubular, having a cylindric, longitudi-
nal passage *a²* extending wholly through it,
from end to end, and has in one side, a lon-
gitudinal slot *a³* communicating with said
passage and terminating a short distance
from each end of the said portion *a*.

From the rear side of the part *a*, about at the center, extends a stem *a⁴*, adapted to connect with the lathe-head, in adjusting the 55 tool for operation or use, the carrier or carriage being held in position in the tail-stock of the lathe.

B is the cutter holder or slide conformed to and fitting exactly, in cross section, the pas- 60 sage *a²* in the part *a* of the carriage A, and carrying, intermediately of its ends, the cutter B' projecting through the slot *a³*. The cutter holder or slide B is connected by a right angled link-bar C to an index D pivoted 65 upon the part *a* of the carriage A, by a pivot-
screw *b* passing through a hub-like enlarge-
ment *b'*, with the upper edge of which is
formed said index, while said link has at one
end a pivot-screw and slot connection *c, c'* 70
with a short arm *c²* projecting from the lower
edge of said hub, in alignment with said in-
dex. The opposite end of the link bar C has
a pivot-screw *c³* passing through a sleeve *c⁴*,
formed therewith, and screwed into a prefer- 75
ably spherically headed plug or pin *c⁵* re-
movably let into one end of the cutter holder
B, being held therein by a screw *c⁶*.

E is a finely graduated quadrant or scale
superposed upon the part *a'* of the carriage 80
A, with its body or plate portion E' preferably
inclined at the sides, making its front straight
edge of less width than its rear rounded edge,
and having in its center a longitudinal, rect-
angular, or plain sided slot *a*, the function 85
of which will appear farther on.

The quadrant plate E' has depending there-
from differently sized studs or posts
e, e', their lesser sized portions passing
through slots *e'* in the plate-portion *a'* of the 90
carriage A, while through their larger dia-
metered portions, below said plate, pass engaging
screws *f* having plain or unthreaded shank
portions bearing or supported in studs *f'* de-
pending from the under side of said plate. 95
This arrangement permits the movement or
adjustment of the quadrant-plate or scale
either forward or backward to provide for
the increasing or decreasing of the cutting
action of the cutter, as will be more fully ap-
parent hereinafter, the screws *f* being turned
to the right if the cutter cuts too coarse or
large and if it cuts too fine or small they are
turned to the left.

5 F is a follower, slide, or plate having beveled side edges let into the slot *d*, in the quadrant plate *E'* having correspondingly beveled or undercut side edges, said follower or slide 10 having a stud *g* upon its upper side, provided with a slot *g'* receiving the index *D* a short distance inward from its rear, free end, and within which the index is free to move while the slide or follower is free to move in said slot. *G* is a clamp also let into the slot *d* and conforming at its ends to the beveled or undercut side edges of said slot to prevent its upward displacement, said clamp being adjusted by a screw *h* bearing in a post or stud *h'* fixed to the quadrant plate *E'*.
 15 *H* is an upright, preferably milled headed screw working in the part *a* of the carriage *A* and engaging the cutter holder *B* to secure it at the required point of adjustment.
 20 The tool or implement being suitably placed in position in the lathe, as above pointed out, and the work also properly juxtaposed therewith, the cutter is adjusted, by suitably manipulating the screw *h*, so as to cause the 25 corner of the cutter to come to center. A cavity is now drilled in the work by actuating the cutter *B'* about two-thirds the diameter of the jewel to be accommodated, after which place the jewel in the slot *d* and adjust the 30 index or finger *D*, after first loosening the screw *H*, so as to bring the slide or follower *F* against one side of the jewel, while care is taken to have the other side of the jewel touch the clamp *G*, and to have the jewel 35 stand centrally of the slot. The screw *H* is now tightened and the drilling resumed, producing an exact setting or cavity for the jewel, the jewel being removed from the slot *D* and seated or set as required.
 40 Having thus fully described my invention, what I claim, and desire to secure by Letters Patent, is—
 1. The combination, with the cutter holder or slide, of an index and quadrant, or scale, 45 and a right-angled link-bar pivotally connected at its ends to said holder and index, respectively, substantially as specified.
 2. The combination, with the cutter holder

or slide, of an index and a quadrant, and a link-bar having pivotal connection with said 50 holder and index, and also adjustable with relation to said index, substantially as set forth.

3. The combination, with the tool or cutter holder, or slide, of an index, means for connecting them together, a quadrant having a slot, and a follower arranged in said slot and adapted to receive said index, substantially as set forth.

4. The combination with the tool or cutter 60 holder of an index, means for connecting them together, a quadrant having a slot, a follower arranged in said slot and adapted to receive said index, a clamp also arranged in said slot and a holding screw for said cutter holder or 65 slide, substantially as described.

5. The combination with the tool or cutter holder or slide, of an index, means for connecting them together, a quadrant, and a set 70 or adjusting screw adapted to secure said cutter holder fixedly, substantially as set forth.

6. The combination with the cutter holder or slide, of an index connected to said holder or slide, and an adjustable quadrant movably connected with said index, substantially 75 as set forth.

7. The combination with the cutter holder or slide and a carriage, of an index connected to said holder or slide, and a quadrant movably connected with said index and having a 80 set screw and slot connection with said carriage, substantially as specified.

8. The combination with a carriage and the cutter holder or slide, of an index connected to said cutter holder or slide and the quadrant movably connected with said index and having an adjustable clamp adapted to engage a jewel held in said carriage, substantially as 85 specified.

In testimony whereof I affix my signature in 90 presence of two witnesses.

L. S. KLING.
